ATTORNEYS

PROTECTIVE HULL WASHER

BACKGROUND OF THE INVENTION

1. Field of the Invention

Protective bumper device for boats.

2. Description of the Prior Art

Hull bumpers, rub rails, pillow cushions or the like have been used since antiquity to protect boats in contact with adjacent members such as pilings, docks, other boats and the like. Prior hereto, however, no known bumper or rub rail device has been adapted for use in washing the hull.

SUMMARY OF THE INVENTION

Accordingly, the present invention adapts a rub rail into a highly useful adjunct for washing boat hulls.

The present invention also provides a highly protective rub rail which is at once uncommonly useful and handsome.

Basically, and not by way of limitation, the present invention provides a resilient conduit fastened circumferentially of the boat at its outermost extremities. In conventional designs in which the hull flares upwardly and outwardly, the outermost extremity is the uppermost portion of the hull. The conduit may be fastened by conventional means or by a resilient snap-on overlay. A conduit is provided with downwardly inwardly directed orifices throughout its length and with a convenient hose connection.

BRIEF DESCRIPTION OF THE DRAWING

FIG. 1 is a top view of the protective hull washer of the present invention shown mounted on a small boat and showing a hose connected thereto.

FIG. 2 is an enlarged fragmentary cross-sectional view taken across line 2-2 of FIG. 1.

FIG. 3 is an enlarged fragmentary partial cross-sectional view of the inlet portion of the protective hull washer of the present invention showing the orifices.

DESCRIPTION OF PREFERRED EMBODIMENTS OF THE INVENTION

Referring to the drawing, the protective hull washer 10 of the present invention comprises a resilient conduit 12 which extends circumferentially of the hull 14 of the boat at the outermost extremities thereof which in conventional designs is the upper portion of the hull. As used herein, hull includes the transom.

Resilient conduit 12 is provided with a plurality of orifices 16 which are directed toward the hull downwardly and inwardly. While any cross-sectional configuration of resilient conduit 12 may be utilized, the preferred cross-sectional configuration would include a relatively planar inner member 20 adapted for close fitting against hull 14, an arcuate outer member 22 adapted to ward off the bumps and grinds of hull to third party (dock, pilings, etc.) clashes and a second rela-

tively planar member directed inwardly and downwardly of the hull and which includes orifices 16.

At least one inlet connection 30 may be placed in connection with resilient conduit 12 for introduction of water therein.

- 5 5 Each such inlet connection 30 may comprise a threaded male fitting 32 for simplified connection with standard female couplings 34 on water hoses.

Operation of the protective hull washer 10 is exceedingly simple. Water pumped into resilient conduit 12 is forced 10 under pressure through orifices 16 and against hull 14 thereby providing simplified means for washing the hull. Water pressure should be adequate to fill resilient conduit 12 with water in its entirety. If water pressure is insufficient for this purpose, additional inlet couplings 30 may be utilized at spaced intervals.

Resilient conduit 12 may be fastened to hull 14 in any conventional manner. For appearance and ease of replacement a snap-on covering 40 may be utilized. Snap-on covering 40 is provided with a keyed slot 42 longitudinal of the boat and an arcuate flange 44 adapted to enclose resilient conduit 12. A bracket 46 is conventionally fastened to hull 14. Snap-on covering 40, which is also of resilient material, is snapped around bracket 46 which is mated to keyed slot 42 thereby securing snap-on covering 40 and resilient conduit 12 enclosed thereby to the boat.

While the foregoing is illustrative of preferred embodiments of the present invention, other embodiments and modifications may be had within the teachings hereof and the scope of the claims. For example, either conduit 12 or covering 40, or 30 both, may be aluminum extrusions which would, of course, reduce their characteristics but which would introduce other desirable properties such as structural integrity and durability. An aluminum cover 40 need not necessarily be snapped on to a bracket but may be secured by any conventional means.

I claim:

1. A protective hull washer in accordance with the teachings hereof, comprising:

a. a conduit, said conduit extending circumferentially of the boat;

b. securing means, said securing means securing said conduit to a boat and comprising:

i. a bracket fastened to the boat; and

ii. a covering adapted to the shape of said bracket to be removably secured thereto and having a flange adapted to enclose said conduit against the boat;

c. at least one water inlet for introducing water under pressure to said conduit; and

d. water outlet means, said water outlet means comprising a plurality of orifices in said conduit throughout its length.

2. A protective hull washer in accordance with claim 1, wherein:

a. said conduit is provided with a first substantially planar wall adapted for close contact with the boat; and

b. said conduit is further provided with a second substantially planar wall which includes said water outlet means.
